UNITED STATES PATENT OFFICE.

HENRY S. WING, OF ASHTABULA, OHIO, ASSIGNOR TO JENNIE A. WING,
OF SAME PLACE.

CARPET-SWEEPER.

SPECIFICATION forming part of Letters Patent No. 259,069, dated June 6, 1882.

Application filed January 7, 1882. (Model.)

To all whom it may concern:

Be it known that I, HENRY S. WING, of Ashtabula, in the county of Ashtabula and State of Ohio, have invented certain new and useful Improvements in Carpet-Sweepers; and I do hereby declare the following, to be a full, clear, and exact description of the invention, such as will enable others skilled in the art to which it pertains to make and use the same.

10 My invention relates to an improvement in carpet-sweepers, the object being to simplify and improve the construction and operation of these devices, and to provide a sweeper of such construction that it may be manufactured at 15 small cost and be durable in use.

With these ends in view the invention consists in combining with the end pieces and pans of a carpet-sweeper a slotted bell-crank lever for dumping said pans.

20 The invention further consists in the combination, with the friction-rollers and brush of a sweeper, of devices of the improved construction hereinafter described for supporting and adjusting said brush.

25 The invention further consists in the parts and combinations of parts, hereinafter fully described, whereby the pans of the sweeper may be tilted or dumped and forced back in operative position by the weight and pressure applied to the sweeper.

The invention further consists of the details of construction hereinafter fully described, and pointed out in the claims.

In the accompanying drawings, Figure 1 represents a perspective view of a sweeper constructed in accordance with my invention. Fig. 2 is a central vertical section of Fig. 1. Figs. 3 and 4 represent parts in detail. Fig. 5 is a longitudinal section, and Fig. 6 is a modification. Fig. 7 is a section taken through one end of the sweeper to illustrate the stud or journal projecting from the pan.

A represents the casing of the sweeper, having end pieces, B B', between which are pivoted the tilting pans C by pivots e. These pans are each constructed at one end with an inwardly-projecting ear or arm, c', each provided with an inwardly-projecting stud, c² and c³.

D represents a bell-crank lever, pivoted to 50 the inner side of the end B of the casing by a pivot, b. The lower end of this lever is formed with a diagonal slot, b', adapted to receive the stud c² of the pan C. A horizontal slot, b², is formed in the opposite end of the lower arm 55 of the lever to receive the stud c³ of the other pan, C. The upper end of the lever projects through a slot, a, of the casing, and is adapted to register with notches e formed in the end of the top brace, E, of the casing. The under 60 sides of the pans C, at the ends adjacent to the piece B, are provided each with a runner, f, secured to the bottom and side of the pan. The opposite ends of the pans C are each provided with a flange, f', through the lower end 65 of which passes a pivot, f², securing the pan to the end piece B' of the casing. The latter is provided with a central vertical slot, b², and on each side with a diagonal slot, b³. A stud, 70 b⁴, projects from the outer side of each of the flanges f' of the pans, and extends through the diagonal slots b³ of the end piece B', and upon these studs are mounted friction-wheels, G G, one on each side of the central slot, b², of the end piece B'. 75

It will be observed that by the construction thus far described the two pans C may be readily tilted or dumped by means of the bell-crank lever D; also, it will be clear that when said pans are dumped in opposite directions 80 by means of the bell-crank lever the friction-wheels, which are journaled upon studs of the pans, said studs projecting through the diagonal slots of the end piece B', will be carried with the pans in opposite directions, and after 85 the dust in the pans has been removed the latter may be quickly restored to their operative position by striking them upon the floor.

H represents the brush, of the usual circular or roller form, secured in position by the following-described means. One end of the brush-roller is provided with a stud, h, while the opposite end has an annular recess, h', a friction-wheel, h², and a central pivot or stud, h³, projecting from the latter. 90

I represents a bell-crank lever, pivoted to the inner side of the end piece B of the casing by a pivot, i. The inner end of this lever 95

is provided with a bearing, i' , adapted to receive the stud h of the brush-roller. The upper end of the lever I projects through a slot, i^2 , of the casing and registers with a notched 5 plate, i^3 , secured to one side of the slot i^2 .

J represent a bracket having its horizontal portion j secured rigidly to the under side of the adjacent end of the overhanging top brace, E. The depending portion j' of the bracket is 10 provided with an upper and a lower slot, lettered j' and j^3 respectively, which are adapted to receive studs from a sliding piece, J'. The latter is also guided between studs j^4 , extending from the inner side of the bracket, and is provided 15 near its lower with a bearing, j^5 , adapted to receive the stud h^3 of the brush-roller.

A horizontally-sliding plate or finger-piece, K, is interposed between the bracket and the bearing-piece J'. It is provided with a diagonal slot, K', and is held by means of a headed stud or rivet, K², which passes through the slot K' and the slot j^2 of the bracket. By this construction the friction-wheel h^2 of the brush is held between the wheels or rollers G G, with 25 which it has frictional contact when the device is in operation. It will be observed that the brush-roller may be adjusted vertically by means of the lever I at one end, and by the sliding finger-piece and its connections at the 30 opposite end.

L represents a handle-socket provided with arms l , the ends of the latter being bent outwardly and secured pivotally in bearings M, secured by screws m to the casing. An elastic 35 washer, m' , surrounds the ends of the arms l within the bearings M. A catch, N, preferably of spring metal, is secured to the top brace at about the center of the latter, and adjacent to the handle-socket L. A rigid brace or bracket, 40 n, secured to the casing below said catch, and to the under side of the latter, serves to support and give rigidity to the catch. By this construction the socket L is adapted to be turned over the catch and securely held, the 45 necessary spring action or yielding of the parts being secured by the use of the elastic washers m' .

Instead of making the catch N and brace or brackets n of two separate pieces, as above described, they can be made of a single piece of metal and answer all the necessary purposes.

In Fig. 5 is represented a modification of the end piece B'. In this figure the diagonal slots b^3 of the end piece B' are avoided and the corners of the piece are cut away, and the ends m^2 m^2 of the pans form part of the end piece, and to these ends m^2 m^2 the friction-wheels G G may be secured by studs, as represented in the other figures.

60 By the construction and arrangement herein described I am enabled to dispense entirely with casings for the friction devices, and moreover produce a friction device of few and simple parts, easily operated, and durable and reliable in use.

It will be apparent that I may make many

slight alterations in the details of construction of my improved sweeper without departing from the spirit of my invention. Hence I would have it understood that I do not limit myself 70 to the exact construction shown and described, but reserve to myself the right to make all such changes of form and construction as may properly fall within the scope of my invention.

Having fully described my invention, what 75 I claim as new, and desire to secure by Letters Patent, is—

1. In a carpet-sweeper, the combination, with the casing and the pivoted pans, of a slotted bell-crank lever connected with and adapted to 80 dump said pans, substantially as set forth.

2. In a carpet-sweeper, the combination, with the casing and the pans, the latter having inwardly-projecting ears and lugs, of a bell-crank lever pivoted to said casing and provided with 85 slots adapted to receive said lugs of the pans, substantially as set forth.

3. In a carpet-sweeper, the combination, with the casing, of pivoted pans and a bell-crank lever adapted to tilt the latter, and the friction-wheels mounted on journals projecting from the ends of the pans and adapted to force the latter back into operative position, substantially as set forth. 90

4. In a carpet-sweeper, the combination, with 95 the casing and pivoted pans, of a slotted bell-crank lever adapted to simultaneously dump said pans, friction-rollers, and a revolving brush constructed and arranged substantially as described, whereby said pans are thrown 100 back into operative position by weight or pressure upon the top of the sweeper, substantially as set forth.

5. In a carpet-sweeper, the combination, with the end piece of the casing, of the pivoted pans 105 provided with outwardly-projecting studs or journals upon which are mounted friction-wheels, substantially as set forth.

6. In a carpet-sweeper, the combination, with the brush and its rollers, of a bell-crank lever 110 pivoted to the casing and provided at its inner end with a bearing for one end of the brush-roller, substantially as set forth.

7. In a carpet-sweeper, the combination, with the casing, of a handle-socket provided with 115 arms adapted to be secured in bearings on the casing, elastic washers surrounding the ends of said arms within the bearings, and a catch secured to the top of the casing and so arranged relative to said socket that the latter 120 will be held thereby, substantially as set forth.

8. In a carpet-sweeper, the combination, with the casing, of the bearings M, the handle-socket L, adapted to receive a handle and provided with arms l , elastic washers m' , catch N, and 125 brace n , substantially as set forth.

9. In a carpet-sweeper, the combination, with the top brace and the brush-roller, of a bracket depending from said brace and provided with guides to receive a sliding bearing supporting 130 one end of the brush-roller, and a sliding finger-piece having a diagonal slot within which

bears a stud projecting from said bearing, substantially as set forth.

10. In a carpet-sweeper, the combination, with the top brace and the brush-roller, of a bracket depending from said brace and provided on its inner side with guides between which is supported a sliding bearing, the lower end of the latter being adapted to a slot in the lower end of the bracket, and a sliding finger-
10 piece having a diagonal slot within which bears

a projecting stud of said sliding bearing, substantially as set forth.

In testimony whereof I have signed this specification in the presence of two subscribing witnesses.

HENRY S. WING.
